YARN WINDING MECHANISM

Oscar V. Payne, Leicester, Mass., assignor to
 Crompton & Knowles Loom Works, Worcester,
 Mass., a corporation of Massachusetts

Application October 13, 1941, Serial No. 414,745

10 Claims. (Cl. 28—55.5)

This invention relates to a winding machine for yarn spools such as used in Axminster looms and it is the general object of the invention to adapt the winding machine for use with spools having barrels of different diameters.

The spools used in Axminster looms have yarn wound thereon with the colors arranged according to the pattern desired. A number of spools all of the same kind are used in one loom and the spools all carry substantially the same length of yarn. A mill is likely to have spools of different barrel diameters, one group of spools being of small diameter, another group of large diameter, while a third group may be of intermediate diameter. Since the start of the winding operation requires that the winding rolls have close driving contact with the spool barrel it is desirable that provision be made for locating the rolls in one setting when winding spools of one diameter, and locating them in other settings when spools of different diameters are to be wound. It is accordingly an important object of my present invention to provide means for giving the rolls various relative settings at the start of the winding operation to permit the winding machine to operate satisfactorily with spools of different diameters.

In my prior Patent No. 1,996,305 I have shown a winding machine wherein two rolls normally stationary during the winding operation cooperate with a third movable roll movable away from the other two rolls during the winding operation. After the winding operation is completed the full spool will be removed and the movable roll returned to starting position by movement toward the normal position of the other rolls. It is a further object of my present invention to provide variable stop means to locate the movable roll at different distances from the stationary rolls so that spools of different barrel diameters may be employed.

In the previously mentioned patent I have shown a disk or the like which moves with the movable roll and it is a further object of my present invention to provide a manually operated mechanism having a plurality of stops for engagement with a part of the disk to cause the latter to stop the movable roll in different positions for the purposes already mentioned.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a vertical section through a winding machine such as shown in my previously mentioned patent with my present invention applied thereto.

5 Figs. 2 and 3 are detailed sections on an enlarged scale on lines 2—2 and 3—3, respectively, of Fig. 1.

Fig. 4 is a plan view looking in the direction of arrow 4, Fig. 3.

10 Fig. 5 is an enlarged rear elevation of the part of Fig. 1 showing the stops, and

Fig. 6 is an enlarged horizontal section on line 6—6 of Fig. 2.

15 Referring to Fig. 1, my invention relates to a winding machine having a frame 10 on which a plurality of winding rolls 11, 12 and 13 are rotatably mounted. In the drawing I have shown only one side of the machine, but it will be understood that much of the structure shown in Fig. 1 is duplicated on the opposite end of the machine. The winding roll 11 is mounted in a bearing 14 fixed to the machine frame and rotates always about a fixed axis. The roll 12 is the tension roll which is moved to the right as viewed in Fig. 1 as the diameter of the spool increases. Roll 12 is continuously rotated in a movable bearing 15 on the upper end of a three-armed lever 16 loosely mounted on a cross shaft 17 supported by fixed bearings on the winding machine frame.

20 The lower part of lever 16 is formed with a segmental gear 20 meshing with a pinion 21 fixed to a cross shaft 22 rotatable on the winding machine frame about a fixed axis. A counterweight 23 is suspended from a chain 24 the upper end of which is wrapped around a segmental winding pulley 25 keyed or otherwise secured to the shaft 22. A segmental ratchet wheel 26 is also fixed to shaft 22 and is normally engaged by one or more pawls 27 mounted upon pivot 28 fixed with respect to the machine frame. A release arm 29 swinging about axis 28 has pins 30 for engagement with the pawls 27. During the winding operation weight W is raised and held elevated by the pawls 27.

25 The lever 16 is also provided with a rearwardly extending arm 32 connected by a rod 33 to the piston 34 of a dash pot 35 the purpose of which is to prevent too rapid return movement of the parts to starting position when the pawls 27 are released.

30 The upper roll 13 is mounted for rotation in an arm 40 pivoted on a short shaft 42 on the frame. A gear 44 is fixed to shaft 42 and rotates in unison with the arm 40. Gear 44 meshes with a

similar gear 45 fixed on the end of cross shaft 17. An arm 46 is fixed to shaft 17 and supports a cylinder 47, which by reason of the gears 44 and 45, serves as a counter-weight for the top cylinder 13 when the latter is moved from the full to the dotted line position shown in Fig. 1 to permit removal of a full spool.

During the operation of the winding machine the upper roll 13 is held in fixed position by a latch 50 pivoted at 51 to the end of arm 40 on which the roll 13 rotates. An upward extension of the latch 50 is connected to a rod 52 which extends across the winding machine and is the means by which the latch 50 may be released. Latch 50 has a stop finger 54 held yieldingly against a finger 55 on arm 40.

The lower end of latch 50 engages a holding pawl 57 loosely mounted on a stud 58 fixed to the winding machine frame. A spring 59 holds the pawl 57 yieldingly in the position shown in Fig. 1 in holding relation with respect to the latch 50. A stop screw 60 on the latch 57 engages the bearing 14 to determine the left hand position of the upper end of pawl 57.

By means of mechanism not shown one or the other of the rolls 11 or 13 will be driven positively, depending upon the direction in which the yarn Y is to be wound on the barrel B of the spool S.

In the operation of the mechanism thus far described the hold pawls 27 will be released prior to the start of the winding operation to permit the weight W to act through pinion 21 and rack 20 to move the pressure or tension roll 12 to the left toward the rolls 11 and 13. During the winding operation the rolls 11 and 13 rotate about fixed axes and as yarn accumulates on the barrel B roll 12 moves to the right, thus rocking lever 16 to cause the segmental rack 20 and pinion 21 to raise the weight W. The hold pawls 27 operate to prevent retrograde movement of the ratchet wheel 26 and therefore hold the roll 12 against movement toward the stationary winding rolls. When the winding operation is completed rod 52 will be manipulated to release the top roll 13 so that it can be swung to the dotted position shown in Fig. 1. At this time the full spool is resting on roll 11 and against roll 12. The spool is then removed and hold pawls 27 raised by means of handle 29 to permit the tension roll 12 to move to the left toward roll 11. A new empty spool is then placed with its barrel in contact with the rolls 11 and 12 and roll 13 is moved from the dotted to the full line position of Fig. 1 and latched in fixed position. The winding operation for the new spool is then started by mechanism not shown herein but fully set forth in my previously mentioned patent.

It is believed that the foregoing description is sufficient to set forth the structure and operation of the type of winding machine to which my invention is applied, and for further understanding of the mechanism and procedure in winding the roll reference may be had to the aforesaid patent.

My present invention provides means for varying the stopping position of the tension roll 12 so that it may cooperate with spools having barrels of different diameters. In carrying my invention into effect I use one of the cross beams 70 of the machine to support a stand 71 in which is rotatably mounted an inclined shaft 72 having a hand wheel 73 at the upper end thereof. A disk 75 is secured to the shaft 72 and is provided with three notches 76, 77 and 78, respectively, each of which can cooperate with the spring

plunger 79 mounted in a small cylinder 80 carried by the stand 71. A spring 81 in cylinder 80 urges the spring plunger toward the periphery of the disk 75 and into the notch under it, and a stop pin 82 is provided to limit motion of the spring plunger under action of the spring.

Shaft 72 passes through a bearing 85 on stand 71 and has secured to its lower end a disk 86 carrying three spaced stop screws 97, 88 and 89, respectively. These stop screws are all located so they can move, one at a time, into the path of surface 90 on the segmental ratchet wheel 26. There is a notch in disk 75 for each stop screw and the plunger 79 holds the flange 86 with one or another of its stop screws in stopping position with respect to surface 90. As shown particularly in Fig. 4 the stop screws are of different lengths and extend different distances from the flange 86 and bearing 85 which limits motion to the left, Fig. 1, of the flange, by engagement with its hub 92.

In the operation of my present invention, and assuming that a spool having a small barrel is to be wound, the hand wheel 73 will be turned to place the shortest of the stop screws in the path of surface 90. As the roll 12 moves to the left as already described it will be able to assume a position relatively close to the rolls 11 and 13 for the accommodation of a small barreled spool.

If, on the other hand, the spool to be wound has a large barrel the longest of the stop screws will be placed in the path of surface 90 by appropriate turning of the hand wheel 73, and as the roll 12 approaches the rolls 11 and 13 it will be stopped at the proper distance to accommodate the large barrel of the spool. The intermediate stop screw can be used to locate the roll 12 in position for proper winding of the spool having an intermediate diameter.

While spools of but three different diameters have been mentioned, and for this reason only three stop screws have been shown in the flange 86, yet it is to be understood that the number of stop screws and their various lengths can be altered so that provision can be made for winding spools having a greater variation in diameter than the number set forth herein.

From the foregoing it will be seen that I have provided simple means for adapting a winding machine for use with spools having different barrel diameters. It is further seen that manual operation of the hand wheel 73 serves to place one or another of the stop screws in the path of surface 90 on the ratchet wheel 26 for the purpose of stopping the roll 12 in correct position as it moves toward the stationary rolls. It will further be seen that the spring plunger 79 will hold the selected stop screw in proper position without further attention by the attendant so that a series of spools all having the same diameter may be wound by a single setting of the flange 86.

Having thus described my invention it will be seen that changes and modifications may be made therein by those skilled in the art without departing from the spirit and scope of the invention and I do not wish to be limited to the details herein disclosed, but what I claim is:

1. In a spool winding machine to wind spools of different barrel diameters, said machine having two rolls normally in stationary position during the winding operation and a third roll moving away from the two rolls as the winding operation progresses and having a return stroke toward the normal position of the two rolls preparatory to another winding operation, posi-

tioning mechanism to stop the third roll on the return stroke thereof toward said two rolls comprising an element movable along a given path when said third roll has its return stroke, connections between said element and third roll to stop the latter on its return stroke when said element is stopped along said given path, a fixed support, a plurality of stops carried by said support and movable one at a time into said given path at different points therealong, and means to move any one of said stops into said path in stopping relation relatively to said element and move the other stops out of said path to cause said one stop to arrest motion of the element and stop the third roll on its return stroke toward said two rolls.

2. In a spool winding machine to wind spools of different barrel diameters, said machine having two rolls normally in stationary position during the winding operation and a third roll moving away from the two rolls as the winding operation progresses and having a return stroke toward the normal position of the two rolls preparatory to another winding operation, positioning mechanism to stop the third roll on the return stroke thereof toward said two rolls comprising an element movable along a given path when said third roll has its return stroke, connections between said element and third roll to stop the latter on its return stroke when said element is stopped along said given path, a plurality of different stops for said element, a carrier for said stops, a fixed support for said carrier with respect to which the latter is movable to position the stops one at a time in the path of the element, and manually operated means to move said carrier relatively to the support to move said stops one at a time into said path of the element to stop movement of the third roll on the return stroke thereof toward said two rolls, the distance between said two rolls and the position at which the third roll is stopped depending upon which of said stops is in the path of said element.

3. In a spool winding machine to wind spools of different barrel diameters, said machine having two rolls normally in stationary position during the winding operation and a third roll moving away from the two rolls as the winding operation progresses and having a return stroke toward the normal position of the two rolls preparatory to another winding operation, positioning mechanism to stop the third roll on the return stroke thereof toward said two rolls comprising an element movable along a given path when said third roll has its return stroke, connections between said element and third roll to stop the latter on its return stroke when said element is stopped, a plurality of different stops for said element movable to different positions in said given path, a fixed support for said stops, and means to move said stops relatively to said support and one at a time into said given path in stopping position with respect to said element, each stop when in said path acting to stop the element and effective by reason of said connections to stop movement of the third roll on the return stroke thereof to said two rolls.

4. In a spool winding machine to wind spools of different barrel diameters, said machine having two rolls normally in stationary position during the winding operation and a third roll moving away from the two rolls as the winding operation progresses and having a return stroke

toward the normal position of said two rolls preparatory to another winding operation, positioning mechanism for the third roll on the return motion thereof comprising a member moving along a given path when said third roll has its return motion, connections between said third roll and member to cause the latter to move and stop when the third roll moves and stops, a rotatable shaft, a fixed bearing for the shaft, a flange on the shaft, a plurality of stops on the flange movable one at a time into said given path, each stop movable into said path at a point different from the points in which the other stops move into the path, and manually operated means to move said stops one at a time into said path to arrest movement of the member along said path and cause stopping of said third roll on the return stroke thereof toward the normal position of said two rolls.

5. In a spool winding machine to wind spools of different barrel diameters, said machine having two rolls normally in stationary position during the winding operation and a third roll moving away from the two rolls as the winding operation progresses and having a return stroke toward the normal position of said two rolls preparatory to another winding operation, positioning mechanism for the third roll on the return stroke thereof comprising a member connected to and moving and stopping with said third roll and moving along a given path when said third roll has its return stroke, a fixed bearing, a shaft rotatable in said bearing, a flange secured to the shaft between the bearing and said member, a plurality of stops of different lengths on said flange movable into said path one at a time, and manual means to turn the shaft to cause the stops one at a time to move into said path to stop said member at any one of several points along said given path depending upon which stop is located in said path, for the purpose of stopping said third roll at various points on the return stroke thereof.

6. In a spool winding machine to wind spools of different barrel diameters, said machine having two rolls normally in stationary position during the winding operation and a third roll moving away from the two rolls as the winding operation progresses and having a return stroke toward the normal position of said two rolls preparatory to another winding operation, positioning mechanism for the third roll on the return stroke thereof comprising a rack connected to and moving and stopping with said third roll when the latter has its return stroke, a pinion meshing with the rack, a disk fixed with respect to the pinion and rotating therewith in a given directed path when said third roll has its return stroke, a plurality of stops arranged at different points along and adjacent to said path, and means to move said stops one at a time into said path to have stopping relation with respect to said disk for the purpose of stopping the third roll at various points on the return stroke thereof.

7. In a spool winding machine to wind spools of different barrel diameters, said machine having two rolls normally in stationary position during the winding operation and a third roll moving away from the two rolls as the winding operation progresses and having a return stroke toward the normal position of the two rolls preparatory to another winding operation, positioning mechanism to stop the third roll on the return stroke thereof toward said two rolls com-

prising an element movable along a given path when said third roll has its return stroke, connections between said element and third roll to stop the latter on its return stroke when said element is stopped as it moves along said given path, a fixed support, a plurality of stops carried by said support and movable one at a time into said path at different points therealong, means to move any one of said stops into said path in stopping relation relatively to said element and move the other stops out of said path to cause said one stop to arrest motion of the element and stop the third roll on its return stroke toward said two rolls, and a yielding lock operative subsequent to movement of any one stop in said given path to hold said stop in said path.

8. In a spool winding machine to wind spools of different barrel diameters, said machine having two rolls normally in stationary position during the winding operation and a third roll moving away from the two rolls as the winding operation progresses and having a return stroke toward the normal position of said two rolls preparatory to another winding operation, positioning mechanism for the third roll on the return stroke thereof comprising a member connected to and moving and stopping with said third roll and moving along a given path when said third roll has its return motion, a fixed bearing, a shaft rotatable in said bearing, a flange secured to the shaft between the bearing and said member, a plurality of stops of different lengths on said flange each movable into said path one at a time, manual means to turn the shaft to cause the stops one at a time to move into said path, and yielding lock means to hold any stop in said path subsequent to manual setting thereof in said path.

9. In a spool winding machine to wind spools of different barrel diameters, said machine having two rolls normally in stationary position during the winding operation and a third roll moving away from the two rolls as the winding operation progresses and having a return stroke to-

ward the normal position of the two rolls preparatory to another winding operation, positioning mechanism to stop the third roll on the return stroke thereof toward said two rolls comprising an element movable along a given path when said third roll has its return stroke, connections between said element and third roll to stop the latter on its return stroke when said element is stopped, a plurality of different stops for said element movable to different positions in said given path, a fixed support for said stops, means to move said stops relatively to said support and one at a time into said given path in stopping position with respect to said element, each stop when in said path acting to stop the element and effective by reason of said connections to stop movement of the third roll on the return stroke thereof to said two rolls, and a yielding lock operative subsequent to movement of any one stop in said given path to hold said given stop in said path.

10. In a spool winding machine to wind spools of different barrel diameters, said machine having two rolls normally in stationary position during the winding operation and a third roll moving away from the two rolls as the winding operation progresses and having a return stroke toward the normal position of the two rolls preparatory to another winding operation, positioning mechanism to stop the third roll on the return stroke thereof toward said two rolls comprising an element movable along a given path when said third roll has its return stroke, connections between said element and third roll to stop the latter on its return stroke when said element is stopped along said given path, a plurality of stops for said element each movable into said path, each stop to enter the path at a point different from the points at which the other stops enter the path, and means to move the stops one at a time into said path.

OSCAR V. PAYNE.
